(57) **CLAIM**

The ornamental design for an embossed battery, as shown and described.

DESCRIPTION

FIG. 1 is a top perspective view of an embossed battery showing our new design;

FIG. 2 is a front elevation view thereof; and,

FIG. 3 is an enlarged detail view of the area indicated in FIG. 1.

The broken lines shown in the drawings show portions of the embossed battery which form no part of the claimed design.

1 Claim, 3 Drawing Sheets

FIG. 1

FIG. 2

FIG. 3
